UNITED STATES PATENT OFFICE

ELZA R. STEALY, OF SHENANDOAH, IOWA

APPLIANCE FOR AND METHOD OF BOXING-IN IMPRESSIONS, DENTURES, AND THE
LIKE

Application filed March 1, 1930. Serial No. 432,576.

The object of my invention is to provide an appliance for, and a method of, boxing-in impressions, dentures and the like for the reception of plaster of Paris or of other plastic material used in making models or casts. In dentistry through the pouring of plaster of Paris of a fluid-like consistency or of other plastic cast-forming material over and into moulds (impressions, dentures and the like), casts are thereby made which are very essential in certain types of laboratory work. Those familiar with dental practice will readily understand the purpose, the importance, the convenience and the advantages of the appliance, and the method pursued in its use and operation from the accompanying drawings of the same and the description of the appliance hereinafter set forth.

One object of my invention and method
20 is to overcome the waste of time and material
resulting from present methods in use in making casts. Another object is to secure casts
that are neater in appearance, also, denser and
25 freer from air bubbles than those secured by
present methods. Other objects and advantages will present themselves as the specification proceeds.

The drawings illustrate a preferred form of the invention, yet it is to be understood that in adapting means to meet specific needs and requirements, the design or construction of the appliance may be varied or changed in the minor details thereof within the scope of the invention as claimed, without departing from the spirit thereof. The appliance may also be used in other arts and practices than that of dentistry, hence I do not limit its field of usefulness to dentistry alone.

For a full understanding of the invention and the merits thereof, reference is to be had to the accompanying description and drawings, in which drawings Figure 1 is a top plan view of the boxing-in appliance for boxing-in impressions, dentures and the like. Figure 2 is a front elevation view of the said appliance on the dotted line $a-a$, Fig. 1, looking in the direction indicated by the arrows, showing the anterior, or front surface or face, of the upright section in detail; also suggesting through the medium of the dotted

or broken lines shown in Figures 1 and 2 and which are designated by the letters B—B, the operation of certain movable and adjustable parts of the appliance; that is, the possible movement of the adjustable section 3 in extension and contraction. Figure 3 is a rear elevation view of the upright section of the appliance on the dotted line $b-b$ of Fig. 1, looking in the direction indicated by the arrows. Figure 4 is a sectional view of the upright section of the appliance on the dotted line $c-c$, Fig. 2, looking in the direction indicated by the arrows. Figure 5 is a sectional view of the upright section of the appliance on the dotted line $d-d$ of Fig. 2, looking in the direction indicated by the arrows. Figure 6 is a view of the flexible strip of celluloid, metal, paper or of any other suitable material which may be used with the appliance. Figure 7 is a longitudinal or side view of the appliance as viewed from the right hand side or adjustable section side of the appliance. Figure 8 is a sectional view of Figure 1 on the dotted line $e-e$, looking in the direction indicated by the arrows. Figure 9 is a sectional view of the adjustable section 3 on the dotted line $f-f$ of Fig. 2, looking in the direction indicated by the arrows. Figure 10 is a view of the adjustable section 3 on the dotted line $g-g$, Fig. 2, looking in the direction indicated by the arrows. Figure 11 is a top plan view of the appliance showing an impression in position upon the base plate and contained within the sides of the appliance; the appliance being shown in part only. Figure 12 is a top plan view of the appliance showing a low-impression and lingual block contained within the sides of the appliance; the appliance being shown in part only. Figure 13 is a longitudinal sectional view of the appliance on the dotted line $h-h$, Fig. 12, looking in the direction indicated by the arrows, showing a lower impression and the lingual block in position in the lingual space upon the base plate and contained within the sides of the appliance; the appliance being shown in part only. Figure 14 is a longitudinal sectional view of the appliance on the dotted line $i-i$, Fig. 1, looking in the direction indicated by the arrows, showing the lower impression and the lingual block in position in the lingual space upon the base plate and contained within the sides of the appliance; the appliance being shown in part only.

with the upright section; the remaining periphery of said block being in contact with the lingual periphery, 27, of the impression or denture mounted upon the appliance.

- 5 The first ten drawings (Figures 1 to 10 inclusive), are, primarily concerned with the construction of my boxing-in appliance; the last five (Figures 11 to 15 inclusive) with the method of use pursued in operating the same.
- 10 In the last five figures, the appliance is shown in part only.

Operation

15 Before mounting an impression, denture or the like upon the appliance, one end of the flexible strip 4 is inserted and secured in the slot 15 in the adjustable section 3; the opposite end of 4 is inserted in the slot 18 in the upright section 2, Figure 1. The impression, denture or the like is now placed upon the base plate of the appliance with the certain desired heel, side or section of said impression, denture or the like in contact with the upright section 2, as shown in Figures 11, 12, 20 25 and 15, and as close as possible to the free end of the flexible strip 4 passing through the slot 18 in 2 (Figures 11 and 12). The adjustable section 3 is then adjusted, as to position, so that its surface adjacent to 30 the impression, denture or the like is in contact with said impression, denture or the like (Figures 11 and 12); the said adjustable section 3 is now secured in said position by 13 on 12 (Fig. 7). The flexible strip 4 through 35 its movement as it passes through the slot 18 in 2 is brought into immediate contact with the periphery of the impression, denture or the like which is being boxed-in. The strip 4 is then completely secured in said position 40 in the slot 18 by the thumb screw 17 (Figures 11 and 12). The slotted slide bar 5 is then brought into position, the U or V section of 45 said bar being in contact with 4, and secured in said position by the thumb nut 21 on 20 (Figures 1 and 7). If further adjustments of 4 and 5 are necessary, they can be easily made. In mounting an upper impression or denture, or a crown or a bridge impression, upon the appliance, the process is as described. In 50 mounting a lower impression or denture, the lingual block 6 is placed in position, said block being composed of such material as is selected by the operator. The heels, 29, of the impression, or denture as the case may be, are placed in contact with 2. The adjustments of 3, 4 and 5 being made as previously described. The plaster or other plastic cast-forming material is now poured into said impression or denture. During and immediately following the pouring of the cast-forming material the appliance may be lightly jarred or vibrated by well known means to settle the cast material.

55 A bite impression, 10, Fig. 15, is mounted upon the appliance in the same manner as a

crown or bridge impression. After the bite impression is properly mounted, the pouring of the cast-forming material selected follows, the upper section 32 of the bite impression 10, Fig. 15, being filled first. After the cast 70 has set or hardened in the upper section, 32 of Fig. 15, the impression is reversed and replaced upon the appliance in the usual manner, the upper surface of the cast 32 now being in contact with the base plate 1: the 75 section 33 of the bite impression now being up, the pouring operation is repeated, the section 33 being thus filled.

80 In case that there is a space between the impression, denture or the like and the flexible strip, or the upright section; or between the lingual block and the lower impression, or denture, said space may be filled with tissue paper or with some other suitable material: this prevents the plastic cast-forming material used from flowing into the said space.

85 Through placing oil or the like upon the metal surfaces of the appliance coming into contact with the cast-forming material, adhesion of the material to the appliance is prevented. These parts of the appliance may also be faced with celluloid for the same purpose: when celluloid is used much smoother casts are secured.

90 Having described my appliance, I claim as my invention:—

1. An appliance for boxing-in impressions, dentures and the like, comprising a base plate, an upright section, an adjustable section adjustably secured to the appliance, and 100 a flexible strip having one end secured to the upright section and the other end attached to the adjustable section in box forming relation, means of adjusting the adjustable section and the flexible strip so as to vary the size 105 and the shape of the box thus formed, the said box thus formed being adapted to contain poured cast-forming material.

110 2. The formation of the walls of a box adjustable in size and shape, for boxing-in impressions, dentures and the like, by means of an upright section, an adjustable section adjustably secured to the upright section, and a flexible strip having one end secured to the adjustable section and the other end secured to the upright section in box forming relation, means of adjusting the adjustable section also the flexible strip so as to vary the size and the shape of the box formed by means 115 of the adjustable section, the upright section and the flexible strip.

120 3. The formation of the walls of a box adjustable in size and shape, for boxing-in impressions, dentures and the like, by means of an upright section, an adjustable section adjustably secured to the upright section, and a flexible strip having one end secured to the adjustable section and the other end adjustably secured to the upright section, means 125 of adjusting the adjustable section also the

flexible strip so as to vary the size and the shape of the box formed by means of the upright section, the adjustable section and the flexible strip of said appliance.

5. 4. The formation of a box for an appliance for boxing-in impressions, dentures and the like by means of a base plate, an upright section, an adjustable section adjustably attached to the upright section, and a flexible strip having one end secured to the adjustable section and the other, or free, end of the said flexible strip adjustably secured to the upright section, means of adjusting the adjustable section and the flexible strip so that the area enclosed by the upright section, the flexible strip and the base plate will vary in size and shape.

5. A box for boxing-in impressions, dentures and the like, comprising a base plate, an upright section, an adjustable section adjustably secured to the upright section, and a flexible strip having one end fastened to the adjustable section and the other end fastened to the upright section, means of adjusting the adjustable section and the flexible strip so that the box formed by the upright section, the adjustable section, the flexible strip and the base plate will vary in size and shape.

6. A box, adjustable in size and shape, for boxing-in impressions, dentures and the like, said box being formed by a base plate, an upright section, an adjustable section adjustably secured to the upright section, and a flexible strip having one end secured in a slot in the adjustable section, and the other, or free, end of said flexible strip passing through a slot in the upright section and adjustably secured in said slot, the lower edge of said flexible strip being in contact with the said base plate.

7. An appliance for boxing-in impressions, dentures and the like, comprising a base plate, an upright section, an adjustable section adjustably attached to the upright section, a flexible strip having one end secured to the adjustable section and the other, or free, end of the said flexible strip adjustably secured to the upright section, an adjustable section adjustably attached to the base plate, means of placing the said adjustable section in contact with the flexible strip and of firmly securing the said adjustable section in said position.

8. An appliance for boxing-in impressions, dentures and the like, comprising a base plate, an upright section, an adjustable section adjustably secured to the upright section, a flexible strip having one end inserted into a slot in the adjustable section and the other, or free, end of the said flexible strip inserted into a slot in the said upright section, means of securing the free end of the said flexible strip in any desired position in the slot in the said upright section, and an adjustable slide bar sec-

tion adjustably attached to the base plate of the said appliance, means of placing the said slide bar section in contact with the flexible strip and of firmly securing the said slide bar section in said position.

9. An appliance of the class described, comprising a base plate, an upright section, an adjustable section adjustably secured to the upright section, and a flexible strip, said flexible strip being adapted to be adjustably fastened at one end to said upright section and at its other end to said adjustable section in box forming relation, the said box being adapted to contain an impression adapted to contain poured cast-forming material.

10. An appliance for boxing-in impressions, dentures and the like, comprising a base plate, an upright section, an adjustable section adjustably secured to the upright section, and a flexible strip of celluloid having one end secured to the adjustable section and the other end adjustably secured to the upright section in box forming relation, said box being adapted to contain a mold adapted to contain poured cast-forming material.

11. A box, adjustable in size and shape, for boxing-in impressions, dentures and the like, said box being formed by a base plate, an upright section, an adjustable section adjustably secured to the upright section, and a flexible strip of celluloid having one end adjustably secured to the upright section and the other end adjustably secured to the adjustable section in box forming relation, means of adjusting the adjustable section and the flexible strip of celluloid so that the said box will vary in size and shape.
